UNITED STATES PATENT OFFICE.

WILLIAM L. KNIGHT, OF FLINT, MICHIGAN.

BEAN-HARVESTER.

1,297,867.

Specification of Letters Patent. Patented Mar. 18, 1919.

Application filed March 28, 1918. Serial No. 225,222.

To all whom it may concern:

Be it known that I, WILLIAM L. KNIGHT, a citizen of the United States of America, residing at Flint, in the county of Genesee and State of Michigan, have invented new and useful Improvements in Bean-Harvesters, of which the following is a specification.

This invention has reference generally to improvements in that class of inventions 10 known as harvesters and more particularly relates to a bean harvester.

It is the primary aim and object of the present invention to provide a machine of the above character designed for cutting 15 bean vines, etc., at a point near the roots so that the vines may be subsequently and readily removed from the ground and deposited in a receiver or catcher thereon on the frame of the machine.

It is an equally important object of this 20 invention to provide a machine of the above mentioned character wherein improved co-operative lifting and elevating mechanism is employed for acting upon the cut vines to 25 consequently assure of the vines being deposited in the receiver on the frame of the machine.

As a further improvement the present invention embraces the provision of a machine 30 of the above character wherein the receiver or catcher into which the cut vines are deposited is capable of dropping the load on the ground, the construction of the receiver being such that it will automatically return 35 to a supported position subsequent to the dropping of the vines upon the same.

More particularly this invention contemplates the provision of novel motion transmitting means for actuating all of the working parts simultaneously during forward 40 movement of the machine.

Among the other aims and objects of this invention may be recited the provision of a device of the character described with a 45 view to compactness, and in which the number of parts are few, the construction simple, the cost of production low and the efficiency high.

Other improvements and novel details in 50 the construction and arrangement of the various parts of the apparatus will be brought out more in detail in the description to follow, which for a clear understanding of the invention should be considered in 55 connection with the accompanying drawings forming a part hereof and wherein is dis-

closed for the purpose of illustration a convenient and satisfactory embodiment of the invention. It is to be noted in this connection that minor changes in the construction and arrangement of parts may be made without departing from the principle of operation of the various parts. 60

The invention is clearly illustrated in the accompanying drawings, in which:— 65

Figure 1 is a side elevation of the machine;

Fig. 2 is a top plan view thereof;

Fig. 3 is a longitudinal section of the invention; 70

Fig. 4 is an elevational detail of the cutters;

Fig. 5 is a detail of the catcher or receiver;

Fig. 6 is a detail of a modified form of the 75 cutters.

Fig. 7 is a detail view of the connection between the catcher and the main frame.

Fig. 8 is a top plan view of the cutting 80 disks shown in Fig. 6.

Similar characters of reference are employed in all the above described views, to indicate corresponding parts.

Referring now, more particularly, to the accompanying drawings, there is provided 85 a frame indicated in its entirety by the numeral 1 being rectangular in form and composed of spaced parallel side bars 2, front and rear cross bars 3 and intermediate cross bars 4. Stub axles 5 are mounted on the side 90 bars 2 and extend outwardly therefrom while journaled on the stub axles are supporting wheels 6. On the inner portion of the hub of one of the wheels 6 are carried sprocket wheels 7 for a purpose that will 95 hereinafter become apparent.

With a view toward providing the improved cutting means a shaft 8 is journaled transversely through the side bars and has mounted on one projecting end thereof a 100 sprocket wheel 9 about which is trained a chain 10 and this chain also operates about the sprocket wheels 7 so as to transmit motion from one of the wheels to the shaft 8. Journaled in suitable bearings 11 on the 105 front bar 3 are vertically arranged shafts 12 in the lower ends of which are rigidly secured by suitable fastening devices 13 disk cutters 14. Bevel gears 15 are carried by the upper ends of the shafts 12 and mesh 110 with other bevel gears 16 carried with the shaft 8. In this connection it is to be noted

that the bevel gears 16 face each other so that the shafts 12 will be rotated in opposite directions. Brackets 17 are secured to one of the cross bars by suitable fastening devices 18 and extend downwardly and outwardly terminating in attaching flanges 19. Cutting shoes or blades 20 are connected to the attaching flanges through the instrumentality of fasteners 21 and are inclined in opposite directions or are positioned divergently with respect to each other and are overlapped slightly by the adjacent cutting disks 14 so as to coöperate with the cutting disks when the latter are rotated to cut the vines at a point adjacent the ground.

As intimated, improved means have been provided for raising or elevating the cut vines. In reducing this feature of the invention to practice an elevating conveyer is employed and preferably consists of side bars 22 through the respective ends of which are journaled shafts 23 and 24 both of which carry rollers 25 over which operates an endless slatted belt 26. This conveyer is swingingly mounted between the side bars of the frame as at 27 the lower end being normally positioned near the ground in the rear of the cutters. In maintaining the parts in such position a segmental rack 28 is carried by one side of the main frame while pivoted centrally thereof is a bell crank lever 29 to one portion of which is pivotally connected a link 30. The outer end of this link is pivotally connected as at 31 to one of the side bars of the conveyer. The opposite portion of the bell crank lever constitutes a handle 32 and has mounted thereon a manually operable pawl 33 designed for engagement with any one of the teeth of the rack bar 28. This pawl of course is swingable with the bell crank lever but when released holds the lever in various adjusted positions consequently maintaining the conveyer in such adjusted position. Coöoperating with the conveyer in assuring of the lifting and placing of the vines on the conveyer is a lifting or beating member indicated in its entirety by the numeral 34. This lifting member in the present instance consists of spaced spiders 35 the opposed arms of which support paddles 36 which, like the arms, are radially arranged with respect to the shaft 37 on which the spiders are mounted. Suitable brackets 38 are mounted on the lower ends of the side bars 22 and serve as a means for rotatably supporting the shaft 37 so that the beating or lifting member will be positioned above the lower end of the conveyer. In operating the beating member and the conveyer simultaneously with the cutting means a sprocket wheel 39 is mounted on one projecting end of the shaft 37 while a chain 40 operates about this sprocket wheel 39 and also about another sprocket wheel 42 carried by the other projecting end of the shaft

8. A gear 43 is carried by the other projecting end of the shaft 37 and meshes with the correspondingly formed gear 44 carried with the projecting end of the lower shaft 24 of the conveyer. By this arrangement it is appreciated that owing to the sprocket and chain connections 39, 40 and 42 the shaft 37 will be rotated simultaneously with the shaft 8 and in the same direction so that the beater or lifting member will throw the vines upon the lower end of the conveyer. During this movement owing to the meshing gears 43 and 44 the endless conveyer will be operated in an opposite direction from the shaft and will conduct the vines upwardly.

Suitable means have been provided for receiving the vines which are deposited from the elevating conveyer, in the present instance consisting of a receiver or catcher indicated in its entirety by the numeral 45. This receiver embodies a plurality of longitudinally extending fingers 46 arranged in spaced relation with each other and secured adjacent their inner ends to a cross supporting bar 47 the inner ends being curved inwardly as at 48 and are bound together by means of a band 49. Loops 50 are formed on the extreme terminals while mounted within and secured to the loops is a sleeve 56. A U-shaped bracket 57 is carried by the rear cross bar of the frame and consists of an intermediate portion 58 and spaced arms 59 between which is mounted a pintle 60 which serves to swingingly support the sleeve 56 of the receiver. In assuring of the automatic dumping of the vines from the receiver when the receiver has become loaded a trip finger 61 is secured rigidly to the sleeve while the outer portion of the trip extends between the arms of the bracket and is normally engaged beneath a lug 63 formed on the intermediate portion 58. Inasmuch as the inner portion of the finger is resilient the weight of the load on the outer portions of the fingers of the receiver will automatically release the outer portion of the trip finger 61 from the lug to permit the receiver to swing downwardly and dump the load. For automatically returning the receiver to a supporting position suitable resilient means are provided, in the present instance consisting of a spring which is coiled as at 64 and positioned about the pintle while the respective ends bear against the bracket 57 and the under portion of the receiver 45 and tensioned so as to lift the receiver after the dumping action. In this connection it is to be understood that the spring has sufficient strength to force the head 62 beneath the lug 63.

In Fig. 6 there is shown a slightly modified form of the invention. In this instance instead of employing the shoes 20 an additional pair of shafts 64 are journaled on the front bar of the frame and are operably con-

nected with the shaft 8 in the same manner as the shafts 12 are connected in the preferred form. Cutting disks 65 are secured to the lower ends of these shafts and co-
5 operate with the adjacent cutting disks 14 the adjacent disks slightly overlapping each other so as to assure of an effective cutting action.

The mode of operation of the present in-
10 vention may be reviewed as follows:—

Assuming that the parts have been as-
15 sembed in the manner described and as indicated in the drawings, upon forward movement of the machine the chain 10 will transmit rotary motion from the sprocket wheel 7 to the sprocket wheel 9 and rotate the shaft 8 in the same direction. Inasmuch as the bevel gears 16 of the shaft 8 mesh with the bevel gears 15 on the
20 shafts 12 the disk cutters 14 will rotate in opposite directions or away from each other and coöperate with the blades or shoes 20 to cut adjacent rows of beans at points near the ground. During this move-
25 ment the beating member will rotate in the same direction as the shaft 8 by reason of the fact that the chain 40 operates about the sprocket wheel 42 and the sprocket wheel 39. Since the gears 43 and 44 mesh
30 with each other the endless conveyer 26 will move rearwardly or upwardly to carry all vines that are thrown thereon by the beater and serves to subsequently deposit the vines in the receiver 45. When a sufficient load
35 has been placed in the receiver or carrier the spring will be released from the lug 63 and will be moved downwardly against the tension of the spring to permit of the dumping action and after this action the coil spring
40 64 will actuate to return the receiver to a self-supporting position.

It is believed that in view of the foregoing description, a further detailed description of the operation of the invention is en-
45 tirely unnecessary. Likewise it is believed that the advantages of the invention will be readily apparent.

As many changes might be made in the above construction and many apparently
50 widely different embodiments of this invention could be made without departing from the scope thereof, and it is intended that all matter contained in the above description or shown in the accompanying drawings shall
55 be interpreted as illustrative and not in a

limited sense, it is also to be understood that the language used in the following claims is intended to cover all the generic and specific features of the invention herein described and all statements of the scope of 60 the invention which as a matter of language might be said to fall therebetween.

Having thus described the invention what is claimed as new and desired to be secured by Letters Patent is:—

65

1. A machine of the character described including a main supporting frame, stub axles carried thereby, wheels journaled on the axles, a sprocket carried with one of the supporting wheels, a transverse shaft journaled in the frame near the forward ends thereof, a sprocket wheel carried by one projecting end of the shaft, a chain operating about both of the sprocket wheels for rotating the shaft simultaneously with the 70 moving of the wheels, a pair of cutting shoes depending from the frame, a pair of vertical shafts journaled in the frame, intermeshing gears carried by the transverse shaft and the vertical shaft so that the vertical shaft will rotate simultaneously with the transverse shaft, a cutting disk carried by the lower ends of the vertical shafts and co-operating with the adjacent shoes, and elevating and conveying mechanism operably 80 mounted on the frame in the rear of the cutters and operably connected with the transverse shaft.

2. In a bean harvester, a main supporting frame, cutting means operably mounted 90 thereon, elevating and conveying mechanism mounted on the frame and operably connected with the cutting means, a bracket secured to the rear end of the frame beneath the upper end of the elevating and conveying mechanism, a pintle mounted through the bracket, a sleeve disposed about the pintle, a receiver connected to the sleeve, a catch formed on the bracket, a resilient trip finger extending from the sleeve and normally engageable beneath the catch and self-releasing when the receiver has become loaded, and a spring member disposed beneath the receiver and connected to the pintle and to the bracket and exerting a tension 95 on the receiver for automatically returning the receiver to a load receiving position subsequent to the dumping action.

In testimony whereof I affix my signature.

WILLIAM L. KNIGHT.
